US0D1113774S

(12) **United States Design Patent** (10) **Patent No.:** **US D1,113,774 S**
(45) **Date of Patent:** **** Feb. 17, 2026**

(54) **SUSCEPTOR**

(71) Applicant: **NuFlare Technology, Inc.**, Kanagawa (JP)

(72) Inventors: **Takuto Umetsu**, Kamakura (JP); **Masataka Iwasaki**, Kawasaki (JP)

(73) Assignee: **NuFlare Technology, Inc.**, Kanagawa (JP)

(**) Term: **15 Years**

(21) Appl. No.: **29/942,796**

(22) Filed: **May 17, 2024**

(30) **Foreign Application Priority Data**

Dec. 1, 2023 (JP) ..... 2023-024989 D

(51) **LOC (15) Cl.** **13-03**

(52) **U.S. Cl.**

USPC **D13/182**

(58) **Field of Classification Search**

Primary Examiner — Amanda Christensen

(74) Attorney, Agent, or Firm — RANKIN, HILL & CLARK LLP

(57) **CLAIM**

The ornamental design for a suscepter as shown and described.

DESCRIPTION

FIG. 1 is a perspective view 1 of a suscepter showing our new design

FIG. 2 is a perspective view 2 thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof; and,

FIG. 9 is a 9-9 cut section end-face enlarged view thereof.

1 Claim, 8 Drawing Sheets
